UNITED STATES PATENT OFFICE.

CHESTER L. ANDERSON AND JAMES T. SMITH, OF SPRINGFIELD, MASSACHUSETTS.

PIPE WRENCH.

1,421,137.

Specification of Letters Patent. Patented June 27, 1922.

Application filed January 29, 1921. Serial No. 440,920.

To all whom it may concern:

Be it known that we, CHESTER L. ANDERSON and JAMES T. SMITH, citizens of the United States of America, residing at

5 Springfield, in the county of Hampden and Commonwealth of Massachusetts, have invented certain new and useful Improvements in Pipe Wrenches, of which the following is a specification.

10 This invention relates to improvements in pipe wrenches of the type in which a fixed and a movable jaw are employed, the movable jaw being pivotally attached to the fixed jaw.

15 An object of the invention is to provide a pipe wrench which is particularly adapted for operation in close proximity to a fixed surface, as a wall or partition. Another object is to provide a pipe-wrench which can 20 be readily adjusted to fit pipes of different sizes.

Referring to the drawings:

Fig. 1 is a side elevational view of the completed wrench showing in full lines how 25 it is adapted to be used in close proximity to a fixed surface, and in dotted lines showing the jaws engaging a pipe of smaller size.

Fig. 2 is a detail view of the jaw that is pivotally attached to the fixed jaw.

30 Fig. 3 is a sectional view on the line 3—3 of Fig. 1 of the joint construction.

Fig. 4 is a sectional view on the line 4—4 of Fig. 1 showing the latch for varying the size or opening of the jaws.

35 Fig. 5 is a detail view of the movable plate.

Referring to the drawings in detail: 1 designates the handle portion of the wrench which is formed with an inclined or tapered end part 1' on which is placed the plate 2 of tempered or hardened material. This plate is formed with the rearwardly extending

40 teeth 2'. It is secured to the handle portion 1 by any suitable means, as the screws 3. 4 is a jaw that is pivotally attached to the handle 1 by means of the plates 5 and 6 (see Fig. 3), and the transversely located pin 7. The plates 5 and 6 are secured to the handle 1 by means of the bolts 8 and 9. The upper and forward edge of the jaw 4 is formed

45 with notches or serrations 10 to receive the cross bar 11 of the holding latch 12. This latch is pivotally attached to the handle 1 by means of the pin 13. 14 is a leaf spring which is secured to the underside of the jaw

50 4. This spring rests upon the inner edge of the handle 1 and acts to normally move the

jaw 4 upward or outward away from the handle. It also serves to retain the cross bar 11 of the latch 12 in place in any one of the serrations or notches 10. It is, of course, 60 understood that the extent of opening of the jaws is determined by the size of the pipe upon which the wrench is to operate. The jaw 4 is provided on the under forward surface with a slidable plate 15, a detail of 65 which in plan view is shown in Fig. 5. This plate is formed with an upwardly extending boss or part 16 having an opening through which passes a pin that is secured to a threaded opening 18 in the end of the jaw, 70 as shown in Fig. 2. This pin is surrounded at its inner end by a coil spring 19 under compression which bears against the bottom of the opening at one end and against the upwardly extending part 16 at its opposite end. The plate is formed with a recess 75 15' to receive the shank of the retaining screw 20, and at the same time permit the plate to slide rearwardly on the jaw 4. This movable plate also permits the wrench to 80 fit and adapt itself to any irregular surfaces in a pipe, in order to obtain a good grip or bite on the pipe.

The size of the opening of the jaw 4 is, 85 of course maintained by the latch 12.

20 designates a section of a pipe upon which the jaws of the wrench are operating. 21 designates in dotted lines a smaller pipe. 22 designates a portion of a fixed wall or partition in close proximity to which the 90 pipes 20 and 21 are located, and the wrench is shown engaging the larger one. By making the ends 23 and 24 of the jaws tapered they can be readily inserted between two pipes that are located near each other, and 95 also placed very close to the partition.

What we claim is:

1. A pipe wrench comprising in combination, with a handle member having a serrated pipe gripping jaw portion on its forward end, of a movable jaw pivotally connected to the handle member and formed with pipe gripping serrations on its forward edge and located opposite the serrations on the handle member, a latch pivotally connected to the handle member and engaging the serrations on the movable jaw member for adjusting the distance between the movable serrated jaw and the handle, the movable jaw having an opening therein, a plate 110 covering the opening and means in the opening to permit the plate to slide on the jaw,

said means including a pin, a spring thereon and a perforated boss on the plate through which the pin passes, as described.

2. A pipe wrench designed for operation in close proximity to a wall or the like, and comprising in combination, a handle member, a serrated plate secured thereto on its forward end, a jaw pivotally connected to the handle member, a movable serrated plate secured thereto, a spring on the pivotally connected jaw for normally moving the ser-

rated plate outward, a latch for varying the distance between the serrated plates of the handle and jaw, the oppositely located forward ends of the handle and jaw being formed with oppositely extending inclined surfaces, as described, whereby the jaws are adapted to operate in close proximity to a fixed surface, as a wall or the like, and between pipes that are close together. 15

CHESTER L. ANDERSON.
JAMES T. SMITH.
